CALENDAR AND MEMORANDUM STAND

Frank S. Schade, Holyoke, Mass., assignor to
National Blank Book Company, Holyoke, Mass.,
a corporation of Massachusetts

Application March 21, 1933. Serial No. 661,910

5 Claims. (Cl. 40—120)

This invention relates to an improved loose leaf holder of the type used with calendar and memorandum sheets.

The features of the invention consist in particular details of construction that provide an improved holder for the user and one that is especially adapted for low cost of production. These features and advantages can be understood best from the specific disclosure in the drawing and following description.

Fig. 1 is a view of the completed holder as it would appear on a desk but without any sheets on the binder rings;

Fig. 2 is a view of the under side of the holder; Fig. 3 is a side view; and

Fig. 4 is a cross-section on line 4—4 of Fig. 1.

The holder shown is made out of one stamped metal piece except for the binder rings and the toggle plates of the loose leaf structure. The 20 front flange is conveniently made in the form of a gutter 2 for pen or pencil. The rear flange 3 is longer and has a backwardly turned flange to serve as a foot 4. The side edges are provided with turned down flanges 5 and 6. Made in this 25 way, the stand may be of quite thin metal and yet appear to be as it is—a sturdy and strong stand.

But I do not claim any features of the sheet metal stand apart from the loose leaf structure 30 and the manner in which the latter is incorporated into the stand. The principal feature of my invention is in the conception of cutting the flat face 1 of the stand so that parallel ears 7 and 8 may be bent out of the plane of the face 35 to complete a spring plate 9 of ring binder loose leaf structure integral with the stand. There is more advantage in this than the mere saving of material.

By getting the back of the spring plate 9 in the 40 same or substantially the same plane as that face 1 of the stand used for supporting the loose leaves in flat inclined position, a better operating relation is obtained. This is due to the fact that the sheets are held by the binder structure in 45 better relation to their support. The preferred arrangement is to have the ears or sides 7 and 8 of the spring plate 9 extend downwardly and then mount the toggle plates 10 and 11 (or wires used as the equivalent of toggle plates) on the 50 bottom side of the stand holder. Then the rings 12 extend through the holder to the top side. This places the rings in the most desirable position for turning the loose leaves of a pad from one side to the other. This position is for the 55 vertical quadrant of the rings to be holding the

loose leaves of the pads as they rest on the flat face of the holder. From this position the leaves can be turned from one side of the holder to the other and all the edges will be more nearly arranged in a vertical plane. The leaves are thus 60 less liable to cramp in turning operations and they lie in better flat pad formation.

The advantages I have mentioned and other advantages result from the structure shown. It will be readily apparent that the holder has the 65 important advantage of simplicity in construction. This simplicity is emphasized in appearance by having the rings appear as the only part of the loose leaf structure showing from the top side of the holder. The fact is that the spring 70 back 9 of the loose leaf structure shows also, but such fact is not at all apparent or suggested in looking at the top side. Such back appears to be merely a central part of the flat top plate 1 of the holder or stand.

I prefer to press out a bead 13 along the center line of the spring back plate 9 to stiffen the plate along this line and between the openings 14 through which the rings extend from below. This bead 13 will normally lie between the two 80 pads on the rings.

While I have shown the ring binder structure arranged centrally in parallel relation to the side edges of the holder, it will be clear that it could be arranged centrally and parallel to the top 85 and bottom edges for a different pad arrangement. In other ways the particular position of the structure and parts might be varied without departing from the essential character of the invention. This character is pointed out in the 90 following claims:

I claim:

1. A loose leaf pad holder comprising a sheet metal stand having a flat pad supporting surface out of which there is bent a pair of parallel downwardly extending ears forming, with the metal of the stand between them, a spring plate member of a ring binder loose leaf structure, said member being an integral part of the stand, 95 said supporting surface having openings for binder rings, and toggle plates carrying binder rings which extend through said openings, said toggle plates being assembled in said spring plate member to complete the ring binder loose leaf structure, all arranged for convenient manufacture and use.

2. A loose leaf pad holder comprising a sheet metal stand having a flat pad supporting surface out of which there is bent a pair of parallel 100 downwardly extending ears forming, with the

metal of the stand between them, a spring plate member of a ring binder loose leaf structure, said member being an integral part of the stand, said supporting surface having openings for 5 binder rings, and toggle plates carrying binder rings which extend through said openings, said toggle plates being assembled in said spring plate member to complete the ring binder loose leaf structure, all arranged for convenient 10 manufacture and use, said supporting surface having a stiffening bead pressed out of the metal of the stand and running longitudinally in the metal between and parallel with the ears.

3. A loose leaf holder comprising a sheet metal 15 stand having an integral flat leaf supporting surface on its top face and openings in said face for the rings of loose leaf structure to extend through when supported on the under side of the stand, toggle supports carrying rings to 20 extend through said openings and above said surface, and a spring plate operatively assembled with the toggle supports on the under side of the stand, said spring plate being formed as an integral part of the sheet metal that serves for 25 the leaf supporting surface.

4. A loose leaf holder for desk use comprising a stand made out of a single sheet of

stamped metal so as to provide an inclined flat support for loose leaf pads so their leaves can be transferred from one pad to the other and a loose leaf ring binder structure to hold such pads on the stand, said structure including rings, and toggle opening and closing means therefor, and a spring plate for the latter means, said spring plate being formed as a stamped part of and integral with said single sheet of stamped metal.

5. A loose leaf holder for desk use comprising a stand made out of a single sheet of stamped metal so as to provide an inclined flat support for loose leaf pads so their leaves can be transferred from one pad to the other and a loose leaf ring binder structure to hold such pads on the stand, said structure including rings, and toggle opening and closing means therefor, and a spring plate for the latter means, said spring plate being formed as a stamped part of and integral with said single sheet of stamped metal, the top surface of said spring plate part being substantially flat and in the plane of the inclined flat support and with the toggle mechanism mounted on the bottom side 100 of the stand.
